METHOD OF HANDLING THREADS

Richard W. Stanley, Drexel Hill, Pa., assignor to
American Viscose Corporation, Wilmington,
Del., a corporation of Delaware

Original application July 17, 1945, Serial No.
605,496. Divided and this application June 28,
1947, Serial No. 757,899. In Canada July 21,
1944

8 Claims. (Cl. 28—72)

1

This invention relates to methods which may be used for the production on a reel of a yarn store which is continuously advanced axially of the periphery of the reel during which time it may be subjected to fluid treatment in the manner and for the purposes conventional in the art. This application is a division of my copending application Serial No. 605,496, filed July 17, 1945, which is in part a continuation of copending application Serial No. 496,543 (now Patent 2,396,297), filed July 29, 1943, in part a continuation of copending application Serial No. 508,174 (now Patent 2,403,031), filed October 29, 1943, and in part a continuation of copending application Serial No. 597,108 (now Patent 2,404,005), filed June 1, 1945.

It is a particular object of the invention in my application Serial No. 605,496 to provide an improved thread-advancing reel. It is a further object of said invention to devise a reel which is adaptable to either a cantilever or double-end supported structure. It is a further object of said invention to provide a reel of this type based upon a structural principle, which, when embodied in a reel of large axial length, results in substantially uniform thread tension and substantially uniform efficiency in thread-advancing action throughout the length of the reel, and at the same time is adapted to operation at high speeds of rotation of the reel. A further object of said invention is to provide an improved system for adjusting the thread-advancing frequency with respect to the rotation frequency of the reel.

A further object of said invention is to provide improved methods of handling a thread or the like in the form of a helix and this constitutes the subject matter of the present application and claims. Further objects and advantages of the invention will be apparent from the drawing and description thereof hereinafter.

In the drawing, illustrative of the invention,

Figure 1 is a mid-section taken axially through one embodiment of a reel for accomplishing the methods of this invention;

Figure 2 is a section taken on line II—II of Figure 1;

Figure 3 is a section taken on line III—III of Figure 1;

Figure 4 is a mid-section taken axially half way through another embodiment of a reel for accomplishing the methods of the invention;

Figure 5 is a section taken on line V—V of Figure 4;

Figure 6 is a view similar to Figure 4, showing

a modified arrangement at the left end of the embodiment of Figure 4;

Figure 7 is a sectional elevation of a form of reel supported from one end only for accomplishing the methods of the invention; and

Figure 8 is a section on line VIII—VIII of Figure 7.

In general, thread-storing, thread-advancing reels for accomplishing the methods of this invention comprise a concentric set of spaced, longitudinally extending bars and an eccentric set of spaced, longitudinally extending bars interdigitating with and alternating between the bars of the first set.

15 The thread carried by the reel is passed continuously through a path having the general form of a helix. Since one set of reel bars is mounted eccentrically to the other set, a portion of the helix is bulged radially outwardly with respect to the true cylinder it would otherwise occupy if it were carried on only the concentric set of reel bars. Because of the practical limitations requiring the bars to have substantial thickness, the bulged portion occupies a minor portion, 20 which is almost but not quite one-half, of the helix circumference. The helix is rotated about a predetermined longitudinal axis and, by rotating the eccentric shaft or bearings for the eccentric set of reel bars, the bulged portion is continuously shifted around the axis. That is, the bulged portion is shifted circumferentially around the helix, the helix being maintained in fixed shape all the while, nevertheless. The reel bars of the eccentric set are actuated or are mounted 25 on a skew axis relative to the axis of the other set so that the turns of thread are shifted longitudinally of the helix in the bulged portion of the helix.

30 Referring first to Figures 1 to 3, the thread-advancing reel comprises two sets of interdigitating bars, the bars 2 of one set alternating with and being spaced from and between the bars 3 of the other set. One of the sets comprising bars 2 is formed by suitably slotting the periphery of a 35 housing formed of the telescoping hollow cylindrical members 4 and 5 of cup-like shape secured together by the bolts 6.

The set of bars 2 is rotatably mounted concentrically on a shaft 7 by means of ball bearings 40 8. One end of the shaft is provided with a cap 9 suitably secured thereto, as by the screw threads shown. The outwardly projecting portion of the cap 9 has a non-circular periphery and fits in a suitable support or hanger 10 having therein a rotatable bearing 9a having a recess 9b of a cross-

section complementary to that of cap 8. The other end of shaft 7 is rotatably supported in a frame member 10a and a gear 10b keyed upon the shaft serves to drive it in either direction or to hold it stationary when desired. A collar 10c held in axial position on the shaft by the cotter pin 10d serves as a thrust bearing for the cap 8c. Packings 11 may be provided to prevent access of liquids to the bearings 8 of the concentric cage or housing.

The other set of bars 3 are divided into several groups (three being shown) those of each group being formed integrally as radial projections from a casting occupying roughly a segment of a circle. Since these three units are identical, only one is described. The segment has a transverse web 12 extending in a plane substantially at right angles to the axis of the reel. The web has an opening 13 which is sufficiently large to allow plenty of clearance about the transverse bolts 6 which secure the housing or cage carrying the concentric bars 2. As shown in Figure 3, the web 12 is provided with a pair of bosses 14 extending axially to both sides of the web. The bosses 14 have bores within which pins 15 are secured by nuts 16. The enlarged ends 17 at the left of the pins 15 have shoulders bearing against a yoke 18 extending between the pair of bosses. The ends 17 are slidably mounted in bores through the spider 19 and the other ends of pins 15 are slidably mounted in similar bores of spider 20. A spring 21 within a recess in spider 20 midway between the pin-receiving bores therein normally presses the entire segment assembly to the left. A roller 22 secured to the yoke 18 bears constantly against the annular cam surface 23 of the cam 24 fixedly secured to the shaft 7. The spiders 19 and 20 are clamped in their appropriate positions upon the sleeve 25 by nut 26, spacer sleeve 27 being inserted between the spiders. The sleeve 25 is carried by bushings 28 and 29, which in turn are carried by the centrally located eccentric portion 30 of the shaft 7. The eccentric causes bars 3 to bulge radially outwardly from the periphery of bars 2 along the upper portion of the reel circumference, as shown. In this embodiment, the bulged portion of the helix projects outwardly to the same extent throughout its length which substantially corresponds to the length of the bars 3. A band 35 of member 4 beyond the bars 3 and having reduced diameter may serve as a surplus thread-collecting ring.

Flexible sealing membranes 31 and 32 may be secured to the segments, the central sleeve assembly, and the concentric cage members (as shown) where it is desired to use the reel for fluid treatment of yarns and the like, and to prevent the entrance of the fluid into the working parts of the reel.

In Figure 1 there is shown in diagrammatic and on a disproportionately reduced scale (as compared to the size of the reel) a driving system for gear 10b comprising a motor 36, a variable speed drive 37, such as the conventional Reeves drive having belts or equivalent means operating between adjustably spaced conical faced pulleys, a transmission housing 38 to reverse the direction of drive by swinging the lever 39 and the output gear 40 in mesh with gear 10b. Any conventional forms of speed-varying and reversing transmission mechanism may be used for the driving purposes just outlined. A similar driving system may be provided for gear 33, if desired, to effect the receiving and delivery of thread at various

speeds and to change the direction of travel of the helix axially of the reel.

Whereas the actuated bars 3 of the invention have been shown assembled in groups upon a plurality of segmental members, it is to be understood that each of the bars 3 may be mounted separately and may be provided with a cam follower to effect its individual actuation axially of bars 2 by means of the cam 24.

10 In operation, the gear 10b may be held in fixed position thereby maintaining the central shaft 7 stationary, and the concentric cage of bars 2 is driven by means of a gear 33 which meshes with gear teeth 34 formed or secured to one end of the concentric cage. The rotation of the concentric cage comprising bars 2 causes the rotation of the segment assemblies of bars 3 about the eccentric shaft 30. As a result of the fact that bars 3 rotate about an axis which is offset from the axis of the bars 2, the thread-carrying surfaces of bars 3 alternately project outwardly and recede inwardly from the periphery formed by bars 2. At the same time, rotation of the segments carrying bars 3 with respect to the cam 24 causes axial motion thereof with respect to the bars 2. This shifts the turns of thread on the reel bars 3 where they bulge from the reel longitudinally of the helix. The arrangement of the eccentric portion 30 of the shaft and the cam surface 23 is so selected that shortly after bars 3 are caused to project outwardly from the periphery of the bars 2, the rise on the cam 24 shifts the bars 3 axially, which axial shift is maintained by a suitable dwell in the cam until after bars 3 have been caused to recede below the peripheral surface of bars 2, after which a drop in the cam surface 23 permits the spring 21 to return the segment to its original position.

Operation in this fashion while holding shaft 40 stationary effects a single complete thread-advancing movement per revolution of the reel bars. However, rotation of shaft 7 provides a means for modifying the pitch of the helical path followed by the thread about the reel. This also shifts the bulged portion of bars 3 continuously around the reel axis. Thus, rotation of shaft 7 in the direction opposite to the rotation of the reel bars and at the same speed causes the pitch to be twice that obtained when the shaft 7 is held stationary. Rotation of shaft 7 at half the speed but in the same direction as the reel bars produces a pitch of one-half that obtained when the shaft 7 is held stationary. Any relative speed may be imparted to the reel bars and the shaft 55 7 carrying the eccentric bearing means 30 and the means 24 for reciprocating the actuatable set of bars.

Referring now more particularly to Figures 4 and 5, the concentric set of longitudinally extending bar members 42 are constituted of a cylindrical-cage member having a flange 44 at one end and an annular member 43 at the other end thereof and being appropriately slotted longitudinally to leave spaces alternating between the bars 43 within which the bars 45 of the other set may be actuated. The cylindrical cage may be clamped between end flanges or spiders 46 and 47 by suitable spaced cap screws 48. The system comprising the cylindrical cage and flanges 44 and 47 constitutes a housing which may have any axial length desired, and which may house the actuating mechanism for the other set of interdigitating bars 45. This housing is supported for rotation with respect to shaft 49 by means of 70 suitable bearings 50 and 51. Flange 47 may be

provided with a non-circular projection 52 which is adapted to fit in a corresponding socket 52" of a coupling 52a upon the shaft 49 which may be driven by the gear 53b keyed thereto. Secured to the shaft 49 is a suitable non-circular projection 53 adapted to be received by a correspondingly shaped recess 53' in a coupling member 53a of a shaft 53" (analogous to 52a and 52") provided with gear 53b keyed thereto for driving it in a direction the same or opposite to that of projection 52. As the occasion may demand, rotation of shaft 49 provides a means of modifying the pitch of the helical path followed by the thread about the reel in the same fashion as mentioned above with respect to Figures 1 to 3. Normally, shaft 49 may be maintained stationary by not rotating gear 53b unless this pitch modification is found necessary. If shaft 49 is rotated at an equivalent speed but in the opposite direction as that of projection 52 the pitch will be twice that obtained when shaft 49 is held stationary. If shaft 49 is rotated at half the speed and in the same direction as projection 52 the pitch obtained will be one-half that obtained when shaft 49 is held stationary.

Two sleeves 54 and 55 are mounted upon the shaft 49 and are suitably spaced by the ring 56. The sleeves 54 and 55 have external cylindrical surfaces whose axes are askew and eccentric to the axis of shaft 49 but parallel to each other. Upon each of the sleeves, a resilient spider member 57 is mounted, preferably by means of ball bearings 58. These spiders 57 are of a resilient material, preferably of thin spring metal, and have individual radially extending members 59 between opposed pairs of which the bars 45 are secured by suitable means, such as by the non-circular rod 60 embedded within depending portions of the bars 45 and the nuts 61. Skew plates 62 and 63 are also carried by the bearings 58 and have outer flanged portions 64 which bear against the ends of the rods 60.

Where it is desired to protect the main operating parts from any possibility of clogging and corrosion when the reel is used for subjecting the filamentary material to liquids, a flexible sealing membrane 65, such as of rubber or synthetic rubber, may be secured to the outer portion of the resilient supporting means for the non-concentric bars and to the ends of the concentric cylindrical cage as shown.

As shown in the modified form in Figure 6, the annular member 42 projects beyond the flange 48 and overhangs the outer rim of a stationary member 46', which surrounds the support 56a. The outer peripheral surface of the member 46' preferably slopes inwardly from its outer rim to a generally cylindrical portion, which serves to hold any accumulation of thread formed after breakage of the thread being handled by the reel or during lacing up of the reel or any machine comprising the reel. Occasionally, stray filaments also tend to gather on this member 46'. The collecting member 46' has a surface of sufficient axial extent to provide adequate storage space and ready access for the operator to remove the accumulated filaments or threads at his convenience without danger of injury to his hands, and without the necessity either of stopping the reel or of giving it immediate attention when the above-mentioned emergencies arise.

In Figure 6, the coupling 53a and attached shaft 53" is retractable from the coupling position shown. The shaft 53" is slidably and rotatably supported in a suitable bearing in the

frame member 88 and a spring 87 normally urges the coupling 53a into engagement with member 13.

In operation of the reels of Figures 4 to 6, the skew plate flanges 84 cause substantial axial motion of the bars 45, such motion being imparted individually to each of the bars 45 by virtue of the individual resilient projecting members 59. By virtue of the eccentricity of the resilient supporting means and the bars 45, the axial to and fro motion of the bars imparted by the skew plates is combined with a radial component of motion which alternately causes first the protrusion of the bars 45 outside the periphery of bars 2 and then their recession within that periphery, thereby resulting in the advancing of the thread axially of the reel. The method of handling a thread in the form of a helix on the reel of Figures 1 to 3 can also be performed in substantially the same way on the reels of Figures 4 to 6, the thread in the helix being maintained under substantially constant tension in all cases.

Figures 7 and 8 show a modification in which the reel is supported from one end only and comprises two generally cylindrical members 70 and 71. Member 70, which may be termed the "concentric member" is mounted concentrically upon and for rotation by and with the drive shaft 72 which may be hollow as shown, as by pins 73 extending into radial recesses or grooves 74. The periphery of member 70 comprises bars 75. Member 71 which may be termed the "eccentric member," is rotatably mounted on bearing 76 the surface of which has an axis eccentric and inclined to that of member 70 and has a periphery comprising a plurality of bars 77 disposed alternately and interdigitating with respect to bars 75 of the concentric member 70. A gear 78 serves to drive shaft 72 and a gear 79 serves to rotate the bearing 76 about the external surface of a stationary supporting sleeve 80, which surface is concentric with the shaft 72 and concentric member 70. A gear 81 integral with or attached to bearing 76 engages the gear 79 to be driven thereby. Optionally, the shaft 72 may be hollow and a thread-receiving member 82 may be stationarily supported upon a rod 83 extending through the shaft and secured to any suitable frame member 84. The member 82 may have a knob 85 to catch thread loops that may be discharged off the end of the reel.

As in the other embodiments, the eccentric and skew bearing sleeve 76 may be maintained in a stationary position or it may be rotated in the same or in opposite directions relative to the shaft 72 and the reel bars. By rotating the bearing sleeve 76 relative to shaft 72, the bulged portion of the helix may be shifted around the axis 60 of the helix. Because of the inclination of the bearing surface of sleeve 76, the bulged portion of the helix projects outwardly to varying extents throughout the length of the helix (i. e., in the direction parallel to its axis).

While the lengths of the reels shown are of the same order of size as their diameter, the reels may be made of any length, regardless of their diameter.

The various parts of the reel may be made of any particular materials desired. The construction of Figures 4 to 6 particularly lends itself readily to making the cylindrical cage members 43, the bar members 45 and bar members 42 associated therewith of materials which offer the most satisfactory bearing surface for

the filamentary material to be handled thereby from the standpoints of smoothness, durability and/or resistance to corrosion under the influence of any liquids with which the filamentary material is to be treated while being advanced longitudinally of the reel, without making the remainder of the reel thereof. This is of tremendous importance from the viewpoints of initial and depreciation costs of such reels, since materials which best meet the requirements specified are generally considerably more expensive than related materials which would be fully adequate for all portions of the supporting structure of the reel other than those intended to contact the filamentary material. Thus, parts 42, 43 and 45 may be made of porcelain, Durez, Al Si Mag, etc., while such other parts as 46 and 47 may be made of Bakelite, stainless steel, etc. These latter parts need not be made of materials which are entirely free of tendencies to be pitted or otherwise superficially altered by the combined action of corrosive chemicals and rubbing action of the filaments handled.

It is to be understood that changes and variations may be made without departing from the spirit and scope of the invention as defined in the appended claims.

I claim:

1. A method of handling a thread or the like which comprises passing a thread continuously through a path having the general form of a helix having a portion thereof bulged radially outwardly relative to the remaining portion thereof, rotating the helix of thread about a predetermined longitudinal axis, continuously shifting the bulged portion around the axis, and shifting the thread turns in the bulged portion longitudinally of the helix.

2. The method of claim 1 in which the bulged portion projects outwardly to the same extent throughout the length of the helix.

3. The method of claim 1 in which the bulged portion projects outwardly to varying extents throughout the length of the helix.

4. The method of claim 3 in which the thread turns in the bulged portion are shifted longitudinally of the helix and the thread in the helix is maintained under substantially constant tension.

5. A method of handling a thread or the like, which consists in maintaining a length of said thread in the general form of a helix, rotating said helix about a predetermined longitudinal axis, maintaining only a portion of said helix radially outwardly bulged relative to the remainder of said helix, shifting said bulged portion circumferentially around the helix while maintaining said helix in fixed shape, and longitudinally forwardly feeding only said bulged part of said helix.

6. A method of handling a thread or the like, which consists in maintaining a length of said thread in the form of a helix, rotating said helix about a predetermined longitudinal axis, maintaining only a portion of said helix radially outwardly bulged relative to the remainder of said helix, shifting said bulged portion circumferentially around the helix while maintaining said helix in fixed shape, and longitudinally forwardly feeding only said bulged part of said helix, said bulged portion of said helix occupying only a minor part of the circumference of the helix.

7. A method according to claim 5, in which the thread of the helix is maintained under substantially constant tension.

8. A method of handling a thread or the like, which consists in maintaining a length of said thread in the form of a helix, wholly and continuously on a support which is rotatable about a longitudinal axis, moving said helix longitudinally on said support without substantially moving said helix circumferentially relative to said support, said helix being thus moved longitudinally, only in a circumferential zone of said helix which is shifted circumferentially around said helix.

RICHARD W. STANLEY.
